(57) CLAIM

I claim the ornamental design for a manual/electric candle grooming tool, as shown and described.

DESCRIPTION

FIG. 1 is a perspective view of a manual/electric candle grooming tool showing my new design;
FIG. 2 is a front end elevational view thereof;
FIG. 3 is a rear end elevational view thereof;
FIG. 4 is a bottom plan view thereof;
FIG. 5 is a right side elevational view thereof; the elevational view of the left side, absent the switch, being a mirror image thereof;
FIG. 6 is a top plan view thereof; and,
FIG. 7 is a perspective view showing the manual/electric candle grooming tool in use; the broken lines depict environmental structure for illustrative purposes only and form no part of the claimed design.
